UNITED STATES PATENT OFFICE

162,946

BARBECUE MACHINE

John S. Francks, Fort Worth, Tex.

Application November 29, 1948, Serial No. 149,869

Term of patent 14 years

(Cl. D81—10)

To all whom it may concern:

Be it known that I, John S. Francks, a citizen of the United States of America, residing at Fort Worth, in the county of Tarrant and State of Texas, have invented a new, original, and ornamental Design for a Barbecue Machine, of which the following is a specification, reference being had to the accompanying drawing, forming part thereof.

I claim:

The ornamental design for a barbecue machine, substantially as shown.

JOHN S. FRANCKS.
